UNITED STATES PATENT OFFICE.

HENRY ALTSHUL, OF HARTFORD, CONNECTICUT.

LOCKING MEANS FOR INCANDESCENT LAMPS.

1,191,934.

Specification of Letters Patent. Patented July 18, 1916.

Application filed December 27, 1913. Serial No. 808,982.

To all whom it may concern:

Be it known that I, HENRY ALTSHUL, a citizen of the United States, residing at Hartford, Hartford county, in the State of Connecticut, have invented certain new and useful Improvements in Locking Means for Incandescent Lamps, of which the following is a full, clear, and exact specification.

My invention relates to improvements in 10 incandescent electric lamps, and the same has for its object more particularly to provide a socket and an incandescent lamp having a base so constructed that the same may be readily inserted into said socket, but 15 when once inserted the same cannot be removed without destroying one of the contacts of said lamp, and thereby rendering the same unfit for use.

Further said invention has for its object 20 to provide a lamp base with a frangible contact which is adapted to engage partly with a coöperating member adapted to be secured within said socket and which will permit of the ready securing of the lamp within 25 said socket, but will prevent the removal of said lamp without breaking said frangible contact, and then render the lamp unfit for use until the same is provided with a new frangible contact.

30 Further said invention has for its object to provide a lamp socket with a locking member which may be made originally as a part of the socket, or be made subsequently and fitted thereto.

35 To the attainment of the aforesaid objects and ends my invention consists in the novel use of construction and in the combination, connection, and arrangement of parts hereinafter more fully described and then 40 pointed out in the claims.

In the accompanying drawings, wherein like numerals of reference indicate like parts—Figure 1 is a side elevation partly broken away and in section, showing a lamp 45 and socket constructed according to and embodying my said invention; the lamp being shown in position for insertion into the socket; Fig. 2 is a similar view showing the lamp base in operative engagement with its 50 socket; Fig. 3 is an enlarged detail side view partly in section, showing the construction of the frangible contact; Fig. 4 is an enlarged bottom view showing the interior of the socket and the locking member therein 55 which engages with said frangible contact;

Fig. 5 is a detail side view of the insulating head disposed within said socket, and the screw-threaded sleeve secured thereto and provided with means for securing the locking member against rotation therein, and 60 Fig. 6 is an enlarged detail perspective view of the locking member adapted to be secured within the lamp socket.

In said drawings 10 designates an incandescent lamp of the usual general construction comprising a bulb 11, a base 12 and a filament 13. The base 12 is formed essentially of a sealing agent 14, formed of insulating material, and a metallic sheath or screw-threaded portion 15 which surrounds 70 said sealing agent 14, and is connected to one terminal 13^a of the filament 13. The top of said base 12 terminates in a tapered or frusto-conical portion 16 within which is embedded the other terminal of the filament 75 13.

17 denotes a circular contact member formed of metal having a central raised portion 17^a adapted to be fitted upon and secured to the frusto-conical portion 16 of 80 the lamp base 12 and frangibly connected to the filament terminal 13^b embedded in said base. The outer edge of said disklike member 17 is slit radially to form members or blades 18, 18 which are bent slightly downwardly. Each of said members or blades 18, 18 has its end transversely inclined, as shown at Fig. 1, so that one of the radial edges thereof lies in a horizontal plane above that of the normal circular line of the edge of 90 said contact member.

The socket member 19 may be of any well known type or form. In the accompanying drawings I have shown the same as comprising an outer shell or casing 20 within 95 which is secured a rigid insulating member 21, preferably made of porcelain, having the base of a screw-threaded sleeve member 22 secured thereto.

The sleeve member 22 is cut out adjacent 100 to its upper edge to receive the lower end of a contact member 23 which is disposed centrally within the screw-threaded sleeve member 22, and insulated therefrom by a disk of mica or other suitable non-conducting material 24. The upper end of said contact 105 23 is adapted for connection with one conductor leading from a source of electric supply, while the threaded sleeve member 22 is adapted for connection, through the 110

medium of the switch or circuit closer 25, with the other conductor leading from said source of electric supply.

26 denotes a locking member which is 5 formed of fiber, or other suitable insulating material and made circular in outline. The said disk is provided with a central opening 27 to receive the raised central portion 17^a of the frangible contact member 17 on 10 the lamp base, and a slight depression 27^a in its upper surface to accommodate the horizontal portion of the contact member 23. The said disk is also provided with a series of radial slits producing downwardly-extending members or blades 28, 28 which have 15 their edges turned slightly in the direction opposite to that of the members or blades 18, 18 of the frangible contact 17.

The locking member 26 is formed of such 20 diameter that when the same is forced into the threaded sleeve member 22 of the socket, the same will be held firmly in place by the frictional and wedging engagement of the edges of said members or blades 28, 28 with 25 the interior wall of the screw-threaded sleeve member 22. In order to secure said locking member 26 against rotation within said sleeve 22, I may, in some instances, when such becomes necessary provide certain of 30 the members or blades 28, 28 in their outer edges with recesses or indentations 28^a, 28^a, and provide the threaded sleeve 22 with correspondingly-shaped, inwardly-extending 35 projections or indentations 29, 29, which will engage with the recesses or indentations 28^a, 28^a provided in the edges of the members or blades 28, 28 of said locking member 26.

The operation of the device will be ob- 40 vious from the foregoing. It may be stated, however, that in order to prevent the removal of a lamp from the socket it merely becomes necessary to insert, first, the locking member 26 within the sleeve member 22 45 of the socket. Hereupon the base of the lamp is inserted into the socket, and screwed home therein in the usual manner. As the upper side of the frangibly-secured contact member 17, and the members 18, 18 thereof, 50 contact with the under side of said locking member 26, and with the members 28, 28 thereof, the rotation or screwing action of the lamp will not be interfered with nor prevented until the upper surface of the 55 central, raised portion or projection 17^a of said contact 17 strikes the contact 23 of the socket. As the members 18, 18 are more or less resilient the same will readily pass below the depressed edges of the members 28, 28 60 of the locking member 26, and interlock therewith. If any attempt be now made to remove the lamp from the socket the unscrewing action will be prevented owing to the raised edges of the members 18, 18, of 65 the contact member 17 striking against the

depressed edges of the members 28, 28 of the locking member 26, and thereby arresting all rotary movement of the lamp. Should the unscrewing action be persisted in, it will result in the rupturing of the 70 connection between the terminal 13^a of the lamp and the contact 17, and thus destroy the operation of the lamp.

It will be observed that by means of my invention I am enabled to provide a locking 75 device which requires merely the attachment of an inexpensive frangible contact member to any ordinary form or type of lamp, and the mere insertion of a coöperating locking member into the lamp socket without altering 80 its construction, no matter what its form or type may be.

Having thus described my said invention, what I claim and desire to secure by Letters Patent is,—

1. The combination with an electric lamp 85 and a socket, of a contact member frangibly secured to one of the terminals of said lamp and comprising locking means, and means within said socket adapted to engage the locking means of said contact member when the lamp is secured to the socket whereby to prevent the removal of the lamp from the 90 socket without detaching said contact member from the terminal, substantially as specified. 95

2. The combination with an electric lamp and a socket, of a contact member frangibly secured to one of the terminals of said lamp, and a coöperating member within said 100 socket, said contact member and said coöperating member being provided with co-acting locking means for locking the lamp within the socket whereby to prevent the removal of the lamp from the socket without 105 detaching said contact member from the terminal, substantially as specified.

3. The combination with an electric lamp and a socket, of a locking device comprising 110 a contact member frangibly secured to said lamp and connected to one of the terminals thereof, engageable means on said contact member, and a coöperating locking member secured to said base, engaging means on said locking member adapted to interlock with the engageable means on said frangible member, whereby to prevent the removal of said lamp from said socket without severing said frangible member from said lamp, and said terminal, substantially as specified. 115

4. The combination with an electric lamp and a socket, of a locking device comprising 120 a contact member frangibly secured to one terminal of said lamp, a series of radial members extending outwardly from said contact member, and a coöperating member secured within said socket, a series of radial members secured to said coöperating member adapted to interlock with the radial members of said contact member whereby 125 130

prevent the removal of said lamp from said socket without rupturing the connection between said contact member and the lamp terminal secured thereto, substantially as specified.

5. The combination with an electric lamp and a socket, of a locking device comprising a contact member frangibly secured to one terminal of said lamp, a series of inclined resilient members extending radially outwardly from said contact member, and a coöperating member formed of insulating material secured within said socket and provided with an opening to receive the contact member above specified of said lamp, and a series of inclined radial members adapted to interlock with the radial members of said contact member whereby to prevent the removal of said lamp from said socket without severing said contact member from the lamp terminal connected thereto, substantially as specified.

6. The combination with an electric lamp and a socket, of a locking device comprising a contact member frangibly connected to one terminal of said lamp, a series of inclined resilient members extending downwardly and outwardly from said contact member and having their ends transversely inclined, a coöperating member formed of insulating material having a central opening adapted to receive the contact member above specified on said lamp, and inclined radial members arranged along the edge of said coöperating member having their ends inclined transversely in a direction opposite to that of the resilient members extending from the contact member secured to said lamp, and adapted to interlock therewith whereby to prevent the removal of the lamp from said socket without severing said contact member from the lamp terminal connected thereto, certain of the radial members of said coöperating member being provided with recesses in their edges, and inwardly extending projections arranged in said socket adapted to engage with the recesses in the edges of the radial members of said coöperating member for securing said coöperating member against rotation within said bracket, substantially as specified.

tact member from the lamp terminal connected thereto, and means for securing said coöperating member against rotation within said socket, substantially as specified.

45

7. The combination with an electric lamp and a socket, of a locking device comprising a contact member frangibly connected to one terminal of said lamp, a series of inclined resilient members extending downwardly and outwardly from said contact member and having their ends transversely inclined, a coöperating member formed of insulating material having a central opening adapted to receive the contact member above specified on said lamp, and inclined radial members arranged along the edge of said coöperating member having their ends inclined transversely in a direction opposite to that of the resilient members extending from the contact member secured to said lamp, and adapted to interlock therewith whereby to prevent the removal of the lamp from said socket without severing said contact member from the lamp terminal connected thereto, certain of the radial members of said coöperating member being provided with recesses in their edges, and inwardly extending projections arranged in said socket adapted to engage with the recesses in the edges of the radial members of said coöperating member for securing said coöperating member against rotation within said bracket, substantially as specified.

65

Signed at Hartford, Hartford county, in the State of Connecticut, this 25th day of November, one thousand nine hundred and thirteen.
